[57] CLAIM

The ornamental design for a combined dial ring and removable center bearing assembly for combination locks and the like, as shown and described.

DESCRIPTION

FIG. 1 is a front perspective view of the combined dial ring and removable center bearing assembly for combination locks and the like embodying my new design; FIG. 2 is a rear exploded perspective view thereof; FIG. 3 is an enlarged front perspective view of the center bearing;

FIG. 4 is a rear perspective view of the center bearing shown in FIG. 3; and

FIG. 5 is a greatly enlarged sectional view of the center bearing taken along the line 5—5 in FIG. 3.
The dial ring has been omitted in FIGS. 3, 4 and 5 for convenience of illustration.
